UNITED STATES PATENT OFFICE.

SHREWSBURY B. MILLER, OF FAIRMONT, WEST VIRGINIA.

SPLICE-BAR.

1,121,749.

Specification of Letters Patent. Patented Dec. 22, 1914.

Application filed April 9, 1914. Serial No. 830,756.

To all whom it may concern:

Be it known that I, SHREWSBURY B. MILLER, a citizen of the United States, residing at Fairmont, in the county of Marion and State of West Virginia, have invented certain new and useful Improvements in Splice-Bars, of which the following is a specification, reference being had therein to the accompanying drawing.

This invention relates to certain new and useful improvements in splice bars for railroad rails, beams and metal bars of all kinds used in connection with structural iron work, the object being to provide a splice joint which is so constructed that the beams or bars to be connected, will be free to move longitudinally in respect to each other in order to allow for contraction and expansion.

Another object of the invention is to provide a splice joint which is so constructed that rivets can be used instead of bolts without any danger of spreading the rivets in connecting the rails or beams together, as the case may be.

Another and further object of the invention is to provide a splice joint which is exceedingly simple and cheap in construction, the splice bars working in connection with spacing sleeves mounted in elongated openings formed in the bars to be connected to allow for the expansion and contraction.

Other and further objects and advantages of the invention will be hereinafter set forth and the novel features thereof defined by the appended claims.

In the drawings—Figure 1, is a vertical transverse section taken through a rail, showing the application of my improved splice bars thereto; Fig. 2, is a longitudinal horizontal section; Fig. 3, is a side elevation showing the elongated openings formed in the webs of the rails and the spacing sleeves in position therein, so as to allow the rails to move in respect to one another; Fig. 4, is a detail view of a slightly modified form of splice bar; Fig. 5, is a longitudinal horizontal section through a slightly modified form of splice bar; and Fig. 6, is a side elevation of a splice bar adapted to be used in connection therewith.

Like numerals of reference refer to like parts in the several figures of the drawings.

In carrying out my improved invention of rail splice bar as shown in order to clearly illustrate the same, I provide the

webs of the rails 1 and 2 with elongated openings 3 and 4 adjacent each end which are adapted to register with openings 5 and 6 formed in the splice bars 7 and 8, said bars being arranged upon the opposite sides of the webs as clearly shown in the horizontal section and are preferably secured together by rivets 9. The splice bars 7 and 8 are spaced slightly from the webs of the abutting rails by spacing sleeves 10 arranged within the elongated openings 3 and 4 upon the rivets 9, said sleeves having a length equal to or slightly greater than the thickness of the web. In this construction, the central portions of the rivets are entirely surrounded by sleeves which are mounted in elongated openings formed in the webs of the rails so that in forming the heads of the rivets, all danger of spreading the same is prevented, and a splice is provided which is exceedingly strong and one which allows the bars to be connected to expand and contract.

While I have shown the same used in connection with rails, it is of course, understood that a pair of bars or beams can be connected with my improved construction of splice in such a manner that the members to be connected will have free movement between the splice bars without reducing the strength of the splice in any way, the spacing sleeves strengthening the rivets and holding the joint bars in proper position in respect to each other.

In the modification shown in Fig. 4, the bar 11 is provided with a circular opening 12 in which is mounted a spacing sleeve 13 having an elongated bore 14 through which the rivet 15 extends in order to allow the bar to move in respect to the rivets which are carried by the splice bars in the same manner as previously described, and in some instances, this construction is found to have advantages over the preferred form.

In the modification shown in Figs. 5 and 6, a construction of splice is illustrated which can be used in connection with rails having the usual form of openings as now in use.

In carrying out my construction of splice bar to be used in connection with rails of this character, I provide splice bars 16 and 17 adapted to embrace the webs 18 and 19 of the rails or members to be connected, said webs being provided with spaced circular openings 20 and 21 adjacent each end through which the connecting rivets 22 and 23 are adapted to pass, as will be later de-

scribed. The splice bar 16 is provided with spaced openings 24 adjacent one end adapted to register with the openings 20 formed in the web 19 and the opposite end of the splice bar 16 is provided with elongated openings 25 adapted to register with the openings 21 in the web 18. The splice bar 17 is constructed substantially identical with the splice bar 16 but is arranged reverse, so that the circular openings formed at one end are brought into transverse alinement with the elongated openings of the splice bar 16 and through which the rivets 23 are adapted to pass, the opposite end of the splice bar which is provided with the elongated openings, receiving the rivets 22 and these rivets are provided with especially constructed enlarged heads 26 so as to completely close the elongated openings formed in the respective ends of the splice bars 16 and 17.

Mounted on the rivets 22 and 23 in the elongated openings formed in the splice bars 16 and 17 are spacing sleeves 27 which have a length equal to or slightly greater than the thickness of the splice bar in order to space the splice bars from the web or hold the same in such position that the webs are free to expand and contract in respect to the splice bars. The opposite ends of the rivets 22 and 23 are swaged to form heads, and it will be seen that by this construction, all danger of the rivets spreading or the sleeve being filled with heated iron by the swaging of the head on the rivet, is dispensed with, as the rivets employed in this construction are formed with heads which extend over the elongated openings and sleeves and the opposite ends of the rivets which pass through the circular openings of the splice bars are formed with heads by the ordinary method now employed.

From the foregoing description, it will be seen that I have provided a splice joint which is so constructed that rivets can be used instead of bolts; the members to be connected, being held firmly between splice bars in such a manner that they are free to move in respect to the splice bars in order to com-

pensate for the expansion and contraction thereof.

50

I claim:

1. In a splice bar, the combination with a pair of members arranged end to end and provided with spaced elongated openings adjacent the ends thereof, of cylindrical spacing sleeves arranged within said openings having a length greater than the thickness of said members, splice bars embracing said members held out of frictional contact with said members by said spacing sleeves, and rivets connecting said splice bars passing through said spacing sleeves.

55

2. In a splice bar, the combination with a pair of members having elongated openings adjacent the ends thereof, of splice bars embracing said members, cylindrical spacing sleeves arranged within the openings of said members and engaging said splice bars at the ends thereof for holding said splice bars out of frictional contact with said members, and rivets passing through said splice bars and spacing sleeves for holding said members together, said rivets having heads contacting with the outer faces of said splice bars.

60

3. In a splice bar, the combination with a pair of members to be connected having elongated openings adjacent the ends thereof, of a splice bar arranged on each side of said members having openings registering with the elongated openings of said members, cylindrical spacing sleeves arranged within the elongated openings of said members having a length greater than the thickness of said members and contacting with the splice bars at the ends thereof for holding said splice bars out of frictional contact with said members, and rivets extending through said splice bars and spacing sleeves.

75

In testimony whereof I affix my signature 90 in presence of two witnesses.

SHREWSBURY B. MILLER.
